ABSTRACT

A connector system for transferring electricity and data. The connector system includes a receptacle and a plug. The receptacle includes a shield, a power contact, a ground contact, and a data contact. The shield includes power apertures through which power conductor segments of the power contact extend, ground apertures through which ground conductor segments of the ground contact extend, and a data aperture through which a shield member and a data conductor of the data contact extend. The plug includes another power contact connected to a power wire, another ground contact connected to a ground wire, and another data contact. The plug is receivable by the receptacle to electrically connect the power wire conductor to the power conductor segments of the receptacle, to electrically connect the ground wire conductor to the ground conductor segments of the receptacle, and to electrically connect the data contact to the other data contact, respectively.

COMBINED POWER AND DATA CONNECTOR SYSTEM**CROSS-REFERENCE TO RELATED APPLICATION(S)**

This application claims priority to and the benefit of U.S. Provisional Application No. 62/398,816, filed Sep. 23, 2016, the entire disclosure of which is incorporated by reference herein.

TECHNICAL FIELD

This disclosure relates to electrical connectors and, in particular, connector systems for forming both power and data connections.

SUMMARY

According to an exemplary embodiment, a connector system includes a receptacle assembly and a plug assembly. The receptacle assembly is configured to receive the plug assembly to form separate electrical connections to form a data pathway and a power pathway. The receptacle includes an electromagnetic shield structure that the data pathway and the power pathway pass through and are electrically insulated therefrom.

According to another exemplary embodiment, a connector system provides power and data coupling. The connector system includes a cable, a plug connector, and a base. The cable includes a data conductor, a shielding layer, a first power conductor, and a second power conductor. The plug connector is mechanically coupled to the cable, and includes a data terminal, a first annular member, a first power terminal, and a second power terminal, which are electrically coupled to the data conductor, the shielding layer, the first power conductor, and the second power conductor of the cable, respectively. The annular member is positioned radially between the first power terminal and the second power terminal, and the data terminal is positioned within the annular member. The base is configured to receive the plug connector, and includes a shield structure defining a cavity. The base includes a second data terminal, a second annular member, a third power terminal, and a fourth power terminal, which are positioned in the cavity and are configured to electrically couple to the first data terminal, the first annular member, the first power terminal, and the second power terminal of the plug connector, respectively.

According to another exemplary embodiment, a connector system for transferring electricity and data. The connector system includes a receptacle and a plug. The receptacle includes a shield, a power contact, a ground contact, and a data contact. The shield includes power apertures through which power conductor segments of the power contact extend, ground apertures through which ground conductor segments of the ground contact extend, and a data aperture through which a shield member and a data conductor of the data contact extend. The plug includes another power contact connected to a power wire, another ground contact connected to a ground wire, and another data contact. The plug is receivable by the receptacle to electrically connect the power wire conductor to the power conductor segments of the receptacle, to electrically connect the ground wire conductor to the ground conductor segments of the receptacle, and to electrically connect the data contact to the other data contact, respectively.

2

A connector system is provided for transferring electricity and data, and includes a receptacle assembly and a plug assembly. The receptacle assembly includes a housing, a shield plate, a power contact, a ground contact, and a data contact. The shield plate is connected to the housing and includes multiple power apertures through which the power contact extends, multiple ground apertures through which the ground contact extends, and a data aperture through which the data contact extends. The plug assembly includes another housing, another power contact, another ground contact, and another power contact in the other housing. The plug is receivable by the receptacle assembly to form a seal therebetween, to electrically connect the other power contact to the power contact, the other ground contact to the ground contact, and the other data contact to the data contact. The receptacle assembly is configured to connect to an electromagnetic shield enclosure to form a seal therewith and to electrically connect the shield plate thereto.

BRIEF DESCRIPTION OF THE DRAWINGS

FIG. 1 is a schematic view of a passenger vehicle having a connector system according to an exemplary embodiment.

FIG. 2 is an upper, front, left perspective view of the connector system of FIG. 1.

FIG. 3 is an upper, front right perspective view of a plug and a cable of the exemplary connector system shown in FIG. 2.

FIG. 4 top plan view of the plug and the cable shown in FIG. 3.

FIG. 5 is a cross-sectional view of the cable taken along line 5-5 in FIG. 4.

FIG. 6 is a front elevation view of the connector shown in FIG. 2.

FIG. 7 is a cross-sectional view of the connector taken along line 7-7 in FIG. 4.

FIG. 8A is an upper, front, left perspective view of a receptacle assembly of the exemplary connector system shown in FIG. 2.

FIG. 8B is a rear elevation view of the receptacle assembly shown in FIG. 8.

FIG. 9 is a partial upper, front, left perspective view of the receptacle assembly shown in FIG. 8.

FIG. 10 is a partial front elevation view of the receptacle assembly shown in FIG. 8.

FIG. 11 is another partial upper, front, left perspective view of the receptacle assembly shown in FIG. 8.

FIG. 12 is another partial front elevation view of the receptacle assembly shown in FIG. 8.

FIG. 13 is a cross-sectional view of the receptacle assembly taken along line 13-13 in FIG. 8.

FIG. 14 is a cross-sectional view of the connector system taken along line 14-14 in FIG. 2, which depicts the plug removed from the receptacle assembly.

FIG. 15 is a cross-sectional view of the connector system taken along line 15-15 in FIG. 2, which depicts the plug inserted in receptacle assembly.

FIG. 16 is a front view of another receptacle assembly having multiple combined power/data connection points and multiple data-only connection points.

FIG. 17A is a perspective view of another connector system shown in a first state.

FIG. 17B is a perspective view of the connector system of FIG. 17A shown in a second state.

FIG. 18 is an exploded, perspective view of a receptacle assembly of the connector system of FIG. 17A.

FIG. 19A is a rear view of the receptacle assembly of FIG. 18 shown in a first state of assembly.

FIG. 19B is a rear view of the receptacle assembly of FIG. 18 shown in a second state of assembly.

FIG. 19C is a rear view of the receptacle assembly of FIG. 18 shown in a third state of assembly.

FIG. 19D is a rear view of the receptacle assembly of FIG. 18 shown in a fourth state of assembly.

FIG. 19E is a rear view of the receptacle assembly of FIG. 18 shown in a fifth state of assembly.

FIG. 19F is a rear view of the receptacle assembly of FIG. 18 shown in a sixth state of assembly.

FIG. 20 is an exploded, perspective view of a plug assembly of the connector system of FIG. 17A.

FIG. 21A is a cross-sectional view of the connector system taken along line 21A-21A in FIG. 17A.

FIG. 21B is a cross-sectional view of the connector system taken along line 21B-21B in FIG. 17B.

FIG. 21C is a cross-sectional view of the connector system taken along line 21C-21C in FIG. 17A.

FIG. 21D is a cross-sectional view of the connector system taken along line 21D-21D in FIG. 17B.

FIG. 21E is a schematic detail view of the connector system taken from box 21E-21E in FIG. 21D.

DETAILED DESCRIPTION

Referring to FIG. 1, a connector system 110 is configured to transfer both electrical power and signals (e.g., control and data signals) between a power source 101 and a controller 102 and a module 103 located remotely thereto. The power source 101 and/or the controller 102 may be positioned in an enclosure 104 to which the connector system 110 is coupled. The connector system generally includes a receptacle assembly 120 (e.g., receiver, base, female assembly, female connector, etc.) and a plug assembly 150 (e.g., plug connector, male assembly, male connector, etc.) mechanically and electrically connected to a cable 160. The connector system 110 may, for example, be used in a passenger vehicle 100, or other application.

Referring to FIG. 2, the receptacle assembly 120 provides a combined power/data connection point 222 at which the receptacle assembly 120 receives the plug assembly 150 to provide combined power and data connections (i.e., by providing power transfer and data transfer via separate electrical connections). The receptacle assembly 120 may additionally include one or more data-only connection points 224 at which the receptacle assembly 120 receives other connectors to provide a data-only connection (i.e., by providing data transfer via an electrical connection, which may include incidental power transfer at low levels). The connector system 110 additionally provides electromagnetic shielding to prevent interference that might otherwise occur due to the relatively high electrical output of the power connection (e.g., 48V or 60V at approximately 15 amps), close proximity of other electronic components to the connections formed between the receptacle assembly 120 and the plug assembly 150, and a high prevalence of interference sources in the vehicle 100 (e.g., electrical powertrain, etc.). The connector system 110 may additionally be configured to provide a sealed connection between the receptacle assembly 120 and the plug assembly 150, as well as within the receptacle assembly 120 itself, thereby allowing the connector system 110 to be used in locations of the vehicle 100 that are unenclosed and exposed to external environmental conditions (e.g., rain, snow, dust, etc.). According to alternative embodiments, the receptacle assembly 120 may be

configured with different numbers of combined power/data connection points 222 and data-only connection points 224. For example, as shown in FIG. 16, a receptacle assembly 1620 includes four combined power/data connection points 222 and four data-only connection points 224.

Referring to FIGS. 1-4, the cable 160 is fixedly coupled to the plug assembly 150, so as to be able to transfer both power and data to the module 103. For data transfer, the cable 160 may be configured similar to a coaxial cable, as described in further detail below, but may instead be configured similar to other types of shielded data transfer cables (e.g., shielded twisted pair, etc.).

As shown in the cross-sectional view in FIG. 5, the cable 160 includes a central data conductor 561, an insulator layer 562, and a shielding layer 563, and may additionally include a protective layer 564 (e.g., jacket or additional insulating layer). The cable 160 is also configured to transfer power, and includes appropriate power conductors 568, which may, for example, be round copper cables. The power conductors 568 may be power and ground conductors.

The plug assembly 150 is coupled to the cable 160 and is configured to be received by (e.g., mate with) the receptacle assembly 120, so as to transfer both power and data therewith. Referring to FIGS. 6-7, the plug assembly 150 includes a radially inner portion 650a (e.g., inner or data connector portion) for data transfer and a radially outer portion 650b (e.g., outer or power connector portion) for power transfer. By arranging various data transfer components radially in between the various power transfer components, efficient packaging of combined power and data transfer connector system is achieved. FIGS. 14-15 are cross-sectional views of the plug assembly 150 and the receptacle assembly 120, which illustrate the spatial relationships of the various features thereof.

The plug assembly 150 generally includes, moving radially outward, a data connector 651, an intermediate circumferential gap 654, an intermediate annular portion 655, an outer circumferential gap 656, and an outer annular portion 657. The data connector 651 is provided in the radially inner portion 650a of the plug assembly 150 and includes a female data terminal 651a and an annular member 651b (e.g., plug shield component), which are separated by an inner circumferential gap 652. The plug assembly 150 additionally includes at least two power terminals 658 (e.g., contacts), which are provided in the radially outer portion 650b of the plug assembly 150, as well as one or more annular seal members 459 (e.g., annular seal; shown in FIG. 4). The two power terminals 658 may be power and ground terminals. The power terminals 658 may also be referred to as contacts (e.g., a power contact and a ground contact). The female data terminal 651a may also be referred to as a data contact.

The female data terminal 651a and the annular member 651b of the data connector 651 of the plug assembly 150 are electrically coupled, respectively, to the data conductor 561 and the shielding layer 563 of the cable 160.

The female data terminal 651a of the data connector 651 is additionally configured to receive therein a male data pin 921a of data connector 821 of the receptacle assembly 120 to electrically couple therewith for data transfer. Similarly, the annular member 651b is configured to receive therein another annular member 921b of the data connector 821 to electrically couple therewith to form a continuous shield. It should be noted, however, that these male/female relationships may be reversed, such that the data connector 651 of the plug assembly 150 instead includes a male data pin and an annular member that are received within a female data terminal and an annular member of the data connector 821.

of the receptacle assembly 120. The data connector 821 of the receptacle assembly 120 is discussed in further detail below. The male data pin 921a and the female data terminal 651a may each be referred to as a data terminal.

The intermediate circumferential gap 654 separates the data connector 651 from the intermediate annular member 655 and the power terminals 658, and is configured to receive therein an annular portion 930c of a body member 840 (e.g., molded body) of the receptacle assembly 120, which are discussed in further detail below.

The intermediate annular member 655 of the plug assembly 150 is non-conductive and includes a radially inner portion 655a and a radially outer portion 655b. The radially inner portion 655a has a smaller outer diameter and extends axially further than radially outer portion 655b. A step is, thereby, formed at the axial transition between the radially inner portion 655a and the radially outer portion 655b. The radially outer portion 655b of the intermediate annular member 655 additionally includes a plurality of circumferentially spaced recesses 655c, which correspond to and have received therein the power terminals 658.

The power terminals 658 of the plug assembly 150 are conductive members that are each electrically coupled to one of the power conductors 568 of the cable 160. Each power terminal 658 is positioned in one of the recesses 655c of the intermediate annular member 655. Each power terminal 658 faces radially outward to receive thereagainst a corresponding power terminal 828 (e.g., power and ground terminals) of the receptacle assembly 120 to electrically connect therewith, as discussed in further detail below.

Outer surfaces of the power terminals 658 are spaced apart a greater distance than the outer surface of the radially inner portion 655a and a lesser distance than the outer surface of the radially outer portion 655b. As such, the outer surfaces of the power terminals 658 are radially recessed relative to the outer surface of the radially outer portion 655b and radially proud of the outer surface of the radially inner portion 655a.

The outer circumferential gap 656 of the plug assembly 150 is configured to receive another outer annular portion 1340c and the power terminals 828 of the receptacle assembly 120 therein, as discussed in further detail below.

The outer annular portion 657 and the annular seal members 459 of the plug assembly 150 are configured to be received in and form a seal with a recess 1147 of the receptacle assembly 120, as discussed in further detail below.

The receptacle assembly 120 is configured to receive the plug assembly 150 to transfer electrical power and data therewith. The receptacle assembly 120 is additionally configured to shield electronic components (e.g., the controller 102, PCB, or other electronic components in the enclosure 104) from electromagnetic interference that might otherwise be caused by the power connection of the connector system 110 or otherwise transferred thereto. The receptacle assembly 120 and the plug assembly 150 are also configured to physically engage each other to form a mechanical connection therebetween, while also preventing intrusion of water and debris and maintain robust power and data connections in view of noise, vibration, and harshness (NVH) inputs to the connector system 110.

Referring to FIGS. 2 and 8-15, the receptacle assembly 120 generally includes a data connector 821, two or more power terminals 828, a shield structure 830 (e.g., shield) that includes or is coupled to a front plate 838 (e.g., a forward shield structure), and a body member 840 (e.g., molded component, body, or insert). The two or more power terminals 828 may also be referred to as contacts (e.g., a power contact and a ground contact).

Referring to the partial views in FIGS. 9-10, the shield structure 830 of the receptacle assembly 120 is configured to prevent electromagnetic interference (e.g., electrical noise) caused by any source within the vehicle 100 or an environment of the vehicle 100 from entering the enclosure 104 and impacting the controller 102 or other electrical components (e.g., PCB) therein. For example, the cable 160 might otherwise act as an antenna and form a pathway by which the electrical noise might otherwise enter the enclosure 104. The shield structure 830 of the receptacle assembly 120 is electrically coupled to the shielding layer 563 of the cable 160 and to the enclosure 104. The shield structure 830 thereby provides a path (e.g., a shield pathway), which electrically couples (e.g., grounds) the shielding layer 563 of the cable 160 to the shield structure 830 to the enclosure 104. The shield structure 830 substantially surrounds the power connection that is formed by physical contact between the power terminals 658, 828, respectively, of the plug assembly 150 and the receptacle assembly 120 with the power connections being electrically insulated or isolated from the shield structure 830 (e.g., such that power pathways, such as power and ground pathways or paths, formed by the power connections thereby passes through the shield structure 830 without making contact therewith). The shield structure 830 also substantially surrounds the data connections formed by the physical contact between the data connectors 651, 821 of the plug assembly 150 and the receptacle assembly 120 with the data connections being electrically insulated or isolated from the shield structure 830 (e.g., such that data pathways or paths formed thereby pass through the shield structure 830 without making contact therewith).

For example, the shield structure 830 is a box structure formed of or otherwise comprising appropriate metal material used for electromagnetic shielding. The shield structure 830 defines a cavity 930a (e.g., recess) in which the data connector 821 and the power terminals 828 are positioned. As referenced above, and as is shown in FIG. 1, the shield structure 830 may be recessed into and/or electrically coupled to the enclosure 104.

The enclosure 104 is itself made from an electrically conductive material (e.g., metal and/or conductive polymer) and surrounds (e.g., partially, substantially, or entirely) the controller 102, PCB, or other electronic components in the enclosure 104. The enclosure 104 is configured to shield components contained therein from electromagnetic interference, and may be referred to as an electromagnetic shield enclosure. With the shield structure 830 being electrically coupled to both the shielding layer 563 of the cable 160 and the enclosure 104, the shield structure 830 forms the shield pathway, which electrically connects (e.g., grounds) the shielding layer 563 to the enclosure 104 to prevent propagation of electromagnetic interference into the enclosure 104.

In one example, the shield structure 830 is a multi-component assembly. The shield structure 830 includes a back plate 932 and a peripheral shell 934, which cooperatively form a rear shield structure and define the cavity 930a therein. The back plate 932 forms a rear surface 932a of the cavity 930a. The back plate 932 additionally includes apertures (e.g., apertures 932c) through which the data connector 821 and the power terminals 828 extend into the cavity 930a, so as to be substantially surrounded by the shield structure 830. The back plate 932 includes flanges 932b (e.g., tabs, extensions, etc.) that are bent forward from the rear surface 932a (e.g., at a 90 degree angle, represented by

the broken lines in FIG. 9), and which are electrically and physically coupled to mating surfaces of the peripheral shell 934 (e.g., via laser welding).

The peripheral shell 934 of the shield structure 830 forms outer walls 934a (e.g., four to form a rectangle or square cross-section) of the shield structure 830. The outer walls 934a extend rearward from forward edges 934b (e.g., forward peripheral edge) thereof to or beyond the rear surface 932a of the back plate 932. The forward edges 934b of the peripheral shell 934 include a plurality of members 934c (e.g., fingers, protrusions, etc.) formed integrally therewith. The members 934c are bent or curved inward from the outer walls 934a toward the cavity 930a. The members 934c are spaced apart from each other and cooperatively form the forward edge 934b for receiving and forming an electrical connection with the front plate 838. Among other considerations, maximum dimensions of the gaps or voids between the members 934c may be determined according to the lowest wavelength (and the highest frequency) of the electromagnetic frequency expected. For example, the maximum dimension of the void between the members 934c may be between 1.5 and 10 mm (e.g., approximately 1.5 mm, which corresponds to electromagnetic interference having a frequency of approximately 20 GHz).

Instead of or in addition to the members 934c, a conductive gasket may instead be arranged (e.g., compressed) between the peripheral shell 934 and the front plate 838 to form an electrical connection therebetween and continuously around the shield structure 830.

Thus, the shield structure 830 substantially surrounds the electrical and data connections formed by the physical contact between the data connectors 651, 821 and the power terminals 658, 828 of the plug assembly 150 and the receptacle assembly 120, respectively, by extending behind (e.g., with the back plate 932), around, and forward (e.g., with the outer walls 934a) of such physical contact, while having a forward opening for receiving the plug assembly 150. In other embodiments, the shield structure 830 may be configured in other manners including, for example, comprising fewer or more components (e.g., one integrally formed component, or more than two components coupled together), being proud of or flush with the enclosure 104, or other suitable configurations.

Referring to the partial views in FIGS. 11-12, as well as the cross-sectional views in FIGS. 13-15, the body member 840 is configured to receive the plug assembly 150 and other connectors (e.g., data-only) to form a mechanical connection therewith, so as to facilitate and maintain electrical connections with the data connector 821 and the power terminals 828.

The body member 840 may be a polymer component that may be insert-molded with the shield structure 830, so as to be directly coupled to the shield structure 830. The body member 840 includes a forward portion 1140a that is positioned within the cavity 930a of the shield structure 830, and may also include a rearward portion 1330b (best seen in the cross-sectional view of FIG. 13). The rear portion 1330b is formed continuously with the forward portion 1140a or may be separated therefrom by the shield structure 830 (e.g., being a separate component), but in either instance may be formed via the insert molding process. In other embodiments, the body member 840 may be made from another type of material and/or be made from or coupled to the shield structure 830 in other manners.

The forward portion 1140a of the body member 840 defines one or more recesses 1147 (e.g., recesses) configured to receive one of the plug assemblies 150 or other connectors

(e.g., for data-only; not shown). Each recess 1147 includes therein the power terminals 828 and the data connector 821. Each recess 1147 is of sufficient axial depth to receive the plug assembly 150 there to make appropriate electrical contact between the data connector 821 and the power terminals 828 of the receptacle assembly 120 with the data connector 651 and the power terminals 658, respectively, of the plug assembly 150.

The forward portion 1140a of the body member 840 is additionally configured to seal with the front plate 838. More particularly, the forward portion 1140a of the body member 840 includes a protrusion 1140d, along with a seal member 1132 surrounding the protrusion 1140d. The protrusion 1140d is received in a complementary aperture (not labeled) in the front plate 838, and may be flush with a forward surface thereof.

The seal member 1132 engages and is compressed by a rear surface of the front plate 838 to form a seal between the body member 840 to prevent intrusion of liquids and/or debris into and/or through the receptacle assembly 120. Prior to the front plate 838 being coupled to the receptacle assembly 120, the seal member 1132 is in a relaxed, uncompressed state and is positioned forward of the members 934c of the peripheral shell 934 of the shield structure 830.

The front plate 838 extends laterally outward from the cavity 930a and may also extend laterally inward for the shield structure 830 to further surround the electrical connections (i.e., the physical contact between the data connectors 651, 821 and the power terminals 658, 828 of the plug assembly 150 and the receptacle assembly 120). The front plate 838 is electrically coupled to the shield structure 830 by contacting and/or being welded to the members 934c of the shield structure 830 and/or by both contacting a conductive gasket, as referenced above. The front plate 838 is additionally mechanically coupled directly or indirectly to the shield structure 830 to sufficiently compress the seal member 1132 therebetween to prevent intrusion of water and/or debris therebetween. For example, the front plate 838 may be coupled to the shield structure 830 with mechanical fasteners (e.g., screws or other elongated fasteners) or laser welding (e.g., to the members 934c), other features of or exterior to the shield structure 830 (e.g., tabs, or clips), or other fasteners or other features that draw the back plate 932 and the front plate 838 toward each other (e.g., fasteners extending through the body member 840). Furthermore, the front plate 838 may be part of or coupled to the enclosure 104, such that the enclosure 104 is also mechanically and/or electrically coupled to the shield structure 830.

Referring to FIGS. 11-15, the data connector 821 of the receptacle assembly 120 is positioned centrally within the recess 1147 and laterally (e.g., radially) between the power terminals 828. This arrangement of the data connector 821 between the power terminals 828 in the receptacle assembly 120 corresponds to that for the data connector 651 and the power terminals 658 of the plug assembly 150.

Referring to FIGS. 9 and 13-15, the data connector 821 extends rearward through the back plate 932 of the shield structure 830. As referenced previously, the data connector 821 generally includes a male data pin 921a and an annular member 921b. The data connector 821 may also be referred to as a data contact. The male data pin 921a may also be referred to as a data conductor, while the annular member 921b may be referred to as a shield member.

As shown in FIG. 13, in a forward region forward of the back plate 932 of the shield structure 830, the data connector 821 includes an inner circumferential gap 1321c that separates the male data pin 921a and the annular member 921b.

In a rearward region behind the back plate 932, the data connector includes one or more insulators or mechanical couplings 1321d, 1321e arranged between the male data pin 921a and the annular member 921b. The male data pin 921a may, for example, be positioned axially rearward of a forward end of the annular member 921b, and extend rearward through the back plate 932 of the shield structure 830 (e.g., to be electrically coupled to the controller 102 or other electronic component). The annular member 921b is electrically coupled to the back plate 932 of the shield structure 830 and may also extend therethrough.

When the plug assembly 150 is inserted in the recess 1147 of the receptacle assembly 120, the male data pin 921a of the data connector 821 of the receptacle assembly 120 is received within and contacts the female data terminal 651a of the data connector 651 of the plug assembly 150 to form an electrical connection therebetween. Furthermore, the annular member 651b of the data connector 651 of the plug is received within and contacts the annular member 921b of the data connector 921 of the receptacle assembly 120 to form an electrical connection therebetween, which also electrically couples the shield structure 830 to the shielding layer 563 of the cable 160. With this electrical contact, data and shield connections are formed between the plug assembly 150 and the receptacle assembly 120.

The power terminals 828 extend through apertures 932c in the back plate 932. The power terminals 828 are separated from the annular member 921b of the data connector 821 with an intermediate circumferential gap 1340e and an annular portion 1340c of the body member 840. The annular portion 1340c of the body member 840 may, for example, be coupled to the rear portion 1340b of the body member 840 through the apertures 932c in the back plate 922, such as being formed therewith during the insert-molding process. The power terminals 828 each extend axially along a radially outer surface of the annular portion 1340c, and include a protrusion 1328a that protrudes radially inwardly through apertures (not labeled) of the annular portion 1340c toward, but not in contact with, the annular member 921b of the data connector 821.

When the plug assembly 150 is inserted in the recess 1147 of the receptacle assembly 120, the intermediate annular member 655 of the plug assembly 150, along with the power terminals 658, is received in the gap 1340e. Moreover, the protrusions 1328a of the power terminals 828 in the receptacle assembly 120 are received against the power terminals 658 of the plug assembly 150 to electrically couple therewith. With this electrical contact, a power connection is formed between the plug assembly 150 and the receptacle assembly 120.

The protrusions 1328a of the power terminals 828 of the receptacle assembly 120 may also be positioned within the recesses 655c of the intermediate annular member 655 of the plug assembly 150, which may function to mechanically align the plug assembly 150 with the receptacle assembly 120.

An outer circumferential gap 1340f is positioned radially outward from the annular portion 1340c of the body member 840 and the power terminals 828. When the plug assembly 150 is inserted in the recess 1147 of the receptacle assembly 120, the outer annular portion 657 of the plug assembly 150 is received within the outer circumferential gap 1340f.

The outer annular portion 657 of the plug assembly 150 thereby engages the body member 840 of the receptacle assembly 120 to form a mechanical and/or sealing connection therewith. More particularly, the recess 1147 has an inner periphery 1347a (e.g., an inner radial surface) that is

complementary to the outer annular portion 657 and the annular seal members 459 of the plug assembly 150. For example, the inner periphery 1347a has a diameter that is slightly larger an outer diameter of the outer annular portion 657 of the plug assembly 150 and slightly smaller than an outer diameter of the annular seal members 459, thereby allowing receipt of the plug assembly 150 therein and compressing the annular seal members 459 to form a seal against the inner periphery 1347a of the body member 840.

Referring to FIGS. 17A-21D, another connector system 1710 is configured to transfer both electrical power and signals (e.g., control and/or data signals), for example, between the power source 101 and/or the controller 102 and the module 103 located remotely thereto (see FIG. 1). The connector system 1710 generally includes a receptacle assembly 1720 coupled to an enclosure 1702 (shown partially) and a plug assembly 1750. The enclosure 1702 is a metal enclosure (e.g., a metal box) of which only a single wall 1702a is shown and in which a circuit board (e.g., PCB) 15 may be positioned. The wall 1702a may be a forwardmost wall of the enclosure 1702 or may be recessed relative to other portions of the enclosure 1702 and/or surrounding components (e.g., functional and/or aesthetic covers). The receptacle assembly 1720 is configured to receive the plug assembly 1750 to provide combined power and data connections, more particularly, by providing power transfer and data transfer via separate electrical connections, as well as provide a mechanical connection therebetween. The receptacle assembly 1720 may also be referred to as a receptacle, 20 receiver, base, female assembly, or female connector. The plug assembly may also be referred to as a plug, plug connector, male assembly, or male connector.

The connector system 1710 is configured to provide electromagnetic shielding to prevent or limit interference that might otherwise occur, for example, due to relatively high electrical output of the power connections (e.g., 48V or 60V at approximately 15 amps), due to close proximity of other electronic components to the power and data connections, and/or due to a high prevalence of interference sources 25 in the vehicle 100 (e.g., electric powertrain, etc.). The connector system 1710 is additionally configured to provide a sealed connection between the receptacle assembly 1720 and the plug assembly 1750 to prevent intrusion of external conditions (e.g., rain, snow, dust, etc.) that may be prevalent 30 in vehicular applications.

Referring additionally to FIG. 18, the receptacle assembly 1720 generally includes a housing 1822, a shield plate 1824, a power contact 1826, a ground contact 1828, and a data contact 1830. Generally speaking, the power contact 1826 35 and the ground contact 1828 are configured to transfer or conduct electricity between components internal to and external from the enclosure 1702. The data contact 1830 is configured to transfer data between data components internal to and external from the enclosure 1702. The shield plate 1824 provides electromagnetic shielding. The housing 1822 is mechanically connected to each of the power contact 1826, the ground contact 1828, and the data contact 1830 and to the enclosure 1702, and is further configured to 40 removably receive the plug assembly 1750. The power contact 1826, the ground contact 1828, and the data contact 1830 may also be referred to as terminals.

When referring to various features (e.g., the receptacle assembly 1720, the plug assembly 1750, the power contact 1826, the ground contact 1828, and the data contact 1830), such features and various aspects thereof (e.g., components, features, portions, etc.) thereof may be identified using terms associated therewith (e.g., receptacle, plug, power, ground,

11

or data), numerically (e.g., first, second, third, etc.), and/or in the alternative (e.g., another), so as to distinguish from other features and aspects of the connector system 1710. For example, a “contact portion” of the power contact 1826 may be referred to or identified as a “power contact portion,” so as to distinguish from a “contact portion” of the ground contact 1828 referred to or identified as a “ground contact portion.” The ground contact 1828 may also be referred to as a contact, while the power contact may be referred to as another power contact 1826. The power contact 1826, the ground contact 1828, and the data contact 1830 may also be referred to as a first contact, a second contact, and a third contact, while contact portions thereof may be referred to as a first contact portion, a second contact portion, and a third contact portion, respectively.

Referring first to the power contact 1826, the power contact generally includes a contact portion 1826a, a conductor portion 1826b, and a coupling portion 1826c. The contact portion 1826a is configured to physically contact and, thereby, electrically connect to a corresponding portion of the plug assembly 1750 as discussed in further detail below. As shown, the contact portion 1826a may have a curved cross-section extending in an axially forward direction away from the enclosure 1702, for example, forming a partially cylindrical surface. The power contact 1826 may also be referred to as a contact, contact assembly, or contact structure. The contact portion 1826a may also be referred to as a contact segment.

The conductor portion 1826b extends from the contact portion 1826a into the enclosure 1702, for example, to connect to a circuit board (not shown) arranged therein. As shown, the conductor portion 1826b may extend transversely from a lower end of the contact portion 1826a (e.g., cooperatively forming an L-shape in cross-section), as well as axially rearward thereof. The conductor portion 1826b of the power contact 1826 includes multiple conductor segments 1826b' (e.g., three as shown), which are cooperatively configured (e.g., sized) to satisfy power transfer requirements (e.g., 48V or 60V at 15 amps, as referenced above). Each of the conductor segments 1826b' (e.g., three as shown) may extend axially rearward into the enclosure 1702, and bend transversely (e.g., downward and/or forming an L-shape) for receipt in corresponding connectors of the circuit board. For example, as shown, the conductor segments 1826b' may extend axially in parallel axes in a first plane, and bend to extend vertically downward in parallel axes in a second plane perpendicular to the first plane. Those portions of the conductor segments 1826b' extending axially may be referred to as axial portions, while those portions extending transversely may be referred to as transverse portions. The conductor segments 1826b' may extend a common distance to terminate at a common elevation. As a result, the conductor segments 1826b' of the power contact 1826 may be received in corresponding connectors (e.g., receptacles) of a circuit board that may be arranged horizontally (e.g., parallel with the axis of the receptacle assembly 1720) in the enclosure 1702. In other embodiments, the conductor portion 1826b and the conductor segments 1826b' may be configured in other manners, for example, by being provided in different numbers (e.g., less than or more than three). Still further, the conductor segments 1826b' may extend only in an axial direction (e.g., without being bent), so as to be received in corresponding connectors (e.g., receptacles) of a vertical circuit board (e.g., perpendicular to the axis of the receptacle assembly 1720) in the enclosure 1702.

12

Each of the contact portion 1826a and the conductor portion 1826b, including the conductor segments 1826b', are formed of a suitable electrically conductive material, such as a copper alloy. The contact portion 1826a and the conductor portion 1826b may be a singular member, for example, being formed via a stamping operation. The contact portion 1826a and the conductor portion 1826b may, collectively, be referred to as a conductive member or structure of the power contact 1826.

10 The coupling portion 1826c of the power contact 1826 is configured to mechanically connect to the housing 1822. The coupling portion 1826c is received in a corresponding recess or aperture of the housing 1822 (e.g., L-shaped in cross-section and discussed in further detail below), of the housing 1822 to be mechanically connected thereto (e.g., via a press-fit, adhered, or other form of mechanical connection or combinations thereof).

15 The coupling portion 1826c may also be configured to insulate the conductor portion 1826b of the power contact 1826 from the shield plate 1824. For example, the coupling portion 1826c may include cylindrical portions 1826c' (e.g., sheaths or sheath portions) that are each associated with one of the conductor segments 1826b' that extends therethrough. The cylindrical portions 1826c', along with the conductor segments 1826b', extend through apertures (discussed below) of the shield plate 1824 and prevent physical and, thereby, conductive contact between the conductor segments 1826b' and the shield plate 1824.

20 The coupling portion 1826c is, for example, a polymer material (e.g., nylon) that is overmolded to an intermediate region (hidden by the coupling portion 1826c) of the conductive member that forms the contact portion 1826a and the conductor portion 1826b. The coupling portion 1826c may also be referred to as a plastic, overmolded, or insulative portion or structure. The power contact 1826 may also be referred to as an overmolded contact structure.

25 The ground contact 1828 is configured similarly to the power contact 1826, for example, by generally including a contact portion 1828a, a conductor portion 1828b, and a coupling portion 1828c. Referring additionally to FIGS. 21A-21D, as arranged in the receptacle assembly 1720, the contact portion 1828a, the conductor portion 1828b, and the coupling portion 1828c of the ground contact 1828 are generally radially opposite the contact portion 1826a, the conductor portion 1826b, and the coupling portion 1826c, respectively, of the power contact 1826 relative to an axis of the receptacle assembly 1720. For example, the contact portion 1828a of the ground contact 1828 may be positioned horizontally across from the contact portion 1826a of the power contact 1826, for example, forming an opposite portion of a cylindrical surface. The ground contact 1828 may also be referred to as a contact, contact assembly, or contact structure. The contact portion 1828a may also be referred to as a contact segment.

30 35 40 45 50 55 60 65 60 The forward region of the conductor portion 1828b of the ground contact may be positioned vertically across from the conductor portion 1826b of the power contact 1826. The conductor portion 1828b includes multiple conductor segments 1828b', which extend axially further rearward than the conductor portion 1826b of the power contact 1826. The conductor segments 1828b' (e.g., three as shown), then bend transversely (e.g., downward and/or forming an L-shape) for receipt in corresponding connectors of the circuit board. For example, as shown, the conductor segments 1828b' may extend axially in parallel axes in a third plane (e.g., parallel with the first plane associated with the axial portions of the conductor segments 1826b'), and bend to extend vertically

downward in parallel axes in a second plane perpendicular to the third plane (e.g., parallel with the second plane associated with the transverse portions of the conductor segments **1826b'**). Those portions of the conductor segments **1828b'** extending axially may be referred to as axial portions, while those portions extending transversely may be referred to as transverse portions. As shown, the transverse portions of the conductor segments **1828b'** may be laterally offset from the transverse portions of the conductor segments **1826b'** of the power contact **1826**. In other embodiments, the conductor portion **1828b** and the conductor segments **1828b'** may be configured in other manners, for example, by being provided in different numbers (e.g., less than or more than three). The power contact **1826** and the ground contact **1828** may be arranged in alternative manners relative to each other, for example, with the conductor segments **1826b'** of the power contact **1826** may instead extend further rearward than the conductor segments **1828b'** of the ground contact **1828**. The ground conductor segments **1828b'** may also extend axially (without bending) for receipt in a vertical circuit board as referenced above.

For further details of the ground contact **1828**, including the contact portion **1828a**, the conductor portion **1828b**, and the coupling portion **1828c** of the ground contact **1828**, refer to generally to the discussion of the power contact **1826** above, including discussion of the contact portion **1826a**, the conductor portion **1826b**, and the coupling portion **1826c**, respectively.

The data contact **1830** generally includes a shield member **1830a**, conductor **1830b**, and a dielectric **1830c**. The data contact **1830** extends axially forward away from the enclosure **1702** to connect with corresponding portions of the plug assembly **1750** (i.e., corresponding shield and data portions), extends axially rearward into the enclosure **1702**, and bends transversely for connection to the circuit board (e.g., being L-shaped). More particularly, as arranged in the receptacle assembly **1720**, the data contact **1830** is positioned between (e.g., is surrounded by) the power contact **1826** and the ground contact **1828** (e.g., in axially forward regions outside the enclosure **1702**, and in axially rearward regions inside the enclosure **1702**).

The shield member **1830a** is a substantially tubular member or structure through which the conductor **1830b** and the dielectric **1830c** extend. A forward portion **1830a'** of the shield member **1830a** extends through a corresponding aperture (discussed further below) of the shield plate **1824**. The forward portion **1830a'** may also physically contact and, thereby, electrically couple the shield member **1830a** to the shield plate **1824**. A rearward portion **1830a''** of the shield member **1830a** may have a larger cross-section than the forward portion **1830a'** and the aperture of the shield plate **1824**, such that the rearward portion **1830a''** physically contacts (e.g., axially abuts) and, thereby, electrically couples the shield member **1830a** to the shield plate **1824**. The rearward portion **1830a''** extends axially from the forward portion **1830a'** and additionally bends transversely thereto to connect to the circuit board in the enclosure **1702** (e.g., forming an L-shape). The shield member **1830a** may, for example, be formed of a conductive metal material, such as stainless steel or material plated with stainless steel.

The conductor **1830b** extends through the shield member **1830a** and is electrically isolated or insulated therefrom, for example, by way of the dielectric **1830c** or an air gap in various regions. The conductor **1830b** extends axially forward from the enclosure **1702**, axially rearward into the enclosure **1702**, and bends transversely downward toward the circuit board (e.g., forming an L-shape). As arranged in

the receptacle assembly **1720**, the conductor **1830b** extends parallel with and between the conductor segments **1826b'** of the power contact **1826** and the conductor segments **1828b'** of the ground contact **1828** and may terminate at a common distance (e.g., elevation) therewith for connection to the circuit board. For example, an axial portion of the conductor **1830b** extends parallel with the axial portions of the conductor segments **1826b'** and between the conductor segments **1828b'**, and a transverse portion of the conductor **1830b** extends parallel with and between the transverse portions of the conductor segments **182b'** and the conductor segments **1828b'**.

The conductor **1830b** may, for example, be made of copper alloy (e.g., brass). The conductor **1830b** may also be referred to as a pin.

The shield plate **1824** allows the conductor segments **1826b'** of the power contact **1826**, the conductor segments **1828b'** of the ground contact **1828**, and the data contact **1830** to extend therethrough, while also providing electromagnetic shielding to prevent electromagnetic interference that might otherwise impact data signals. More particularly, the shield plate **1824** provides electromagnetic shielding across an aperture **1802b** (e.g., enclosure aperture) of a wall **1702a** of the enclosure **1702** through which the receptacle assembly **1720** extends. The shield plate **1824** is electrically coupled to the enclosure **1702** with the shield plate **1824** physically contacting the wall **1702a**. For example, a surface of the shield plate **1824** faces and abuts the wall **1702a** of the enclosure **1702** surrounding the aperture **1802b**.

As referenced above, the shield plate **1824** includes apertures through which the conductor segments **1826b'** of the power contact **1826**, the conductor segments **1828b'** of the ground contact **1828**, and the data contact **1830** extend. More particularly, to provide high levels of electromagnetic shielding for high speed data transfer simultaneous with high power transfer (e.g., high current), multiple power apertures **1824a** (i.e., for power conductor segments to pass therethrough) and multiple ground apertures **1824b** (i.e., for ground conductor segments to pass therethrough) are provided.

The size of and spacing between the power apertures **1824a** and the ground apertures **1824b** may be configured to optimize or otherwise improve electromagnetic shielding. Among other considerations, the maximum size (e.g., diameter or other dimension) of the power apertures **1824a** and the **1824b** may be determined according to the lowest wavelength (and conversely the highest frequency) of the electromagnetic frequency expected. For example, the maximum dimension of the power apertures **1824a** and the ground apertures **1824b** may be between 1.5 and 10 mm (e.g., approximately 1.5 mm, which corresponds to electromagnetic interference having a frequency of approximately 20 GHz). For example, the power apertures **1824a** and/or the ground apertures **1824b** may have a diameter of up to 1.5 mm (e.g., having a 1.5 mm diameter). The power apertures **1824a** are spaced apart laterally from each other, as are the ground apertures **1824b** are spaced apart laterally from each other.

As compared to power transfer and shielding by singular, larger power and ground conductors extending through singular, larger apertures through a shield structure, similar power transfer with improved shielding may be provided by multiple, smaller ones of the power conductor segments **1826b'** and ground conductor segments **1828b'** extending through corresponding, smaller ones of the power apertures **1824a** and the ground apertures **1824b**. The shield plate **1824** also includes a data aperture **1824c**, which is central to

the shield plate 1824, such as being generally concentric with the shield plate 1824. The data aperture 1824c may also be arranged between (e.g., radially between) a first group of the power apertures 1824a and second group of the ground apertures 1824b. The power apertures 1824a in the first group may be arranged in a straight line across the shield plate 1824 (i.e., such that the straight line passes through axes of the power apertures 1824a). The ground apertures 1824b in the second group may be arranged in another straight line across the shield plate 1824 (e.g., in such that the other straight line passes through axes of the ground apertures 1824b and may be parallel with the line). Alternatively, the power apertures 1824a and/or the ground apertures 1824b may be arranged in arcs, such as being concentric with an axis of the data aperture 1824c.

The shield plate 1824 may, for example, be a stamped component formed of stainless steel. The shield plate 1824 may also be referred to as a shield, shield member, or shield structure.

As referenced above, the housing 1822 is configured to mechanically connect to the power contact 1826, the ground contact 1828, and the data contact 1830. The housing 1822 is additionally configured to mechanically and sealingly connect to the enclosure, as well as receive and removably retain the plug assembly 1750.

The housing 1822 generally includes a primary housing structure 1834, an external housing structure 1836, and an internal housing structure 1838.

The primary housing structure 1834 is positioned within the aperture 1802b of the wall 1702a of the enclosure 1702, and protrudes from the enclosure 1702. The primary housing structure 1834 may be generally tubular, for example, being generally circular in cross-sectional shape (e.g., annular) or having other cross-sectional shapes at one or more axial locations. The primary housing structure 1834 may, for example, be a unitary member made of a polymer material (e.g., polyamide), for example, via an injection molding process. The primary housing structure 1834 may, alternatively, be a multi-piece component, be made of another material, and/or be made from another manufacturing process. The primary housing structure 1834 may also be referred to as a primary or housing member or structure.

To mechanically connect to the plug assembly 1750, the primary housing structure 1834 defines a primary recess 1734a for selectively receiving the plug assembly 1750 therein. The primary recess 1734a faces away from the enclosure 1702, for example, in a forward direction. The primary housing structure 1834 may additionally include a locking feature 1834a, such as an aperture or recess, to receive a corresponding locking feature of the plug assembly 1750 (as discussed in further detail below).

The power contact 1826, the ground contact 1828, and the data contact 1830 are additionally mechanically connected to the primary housing structure 1834 and held stationary thereto, for example, to prevent movement relative to the shield 1824. Thereby, the contact portion 1826a of the power contact 1826, the contact portion 1828a of the ground contact 1828, and forward portions (e.g., contact portions) of the shield member 1830a and conductor 1830b of the data contact 1830 are stably arranged in the primary recess 1734a of the primary housing structure 1834.

More particularly, referring to FIGS. 19A-19F, the primary housing structure 1834 includes various apertures or recesses that face toward the enclosure 1702 (e.g., in a rearward direction) and in which are received the power contact 1826, the ground contact 1828, and the data contact 1830. The primary housing structure 1834 includes a power

recess 1934b, a ground recess 1934c, and a data recess 1934d. The power recess 1934b is substantially L-shaped in cross-section, so as to receive therein and couple to the coupling portion 1826c of the power contact 1826. The power recess 1934b extends to the primary recess 1734a of the primary housing structure 1834, such that the contact portion 1826a of the power contact 1826 is arranged therein. The power recess 1934b also faces an interior of the enclosure 1702, such that the conductor portion 1826b (i.e., the conductor segments 1826b') of the power contact 1826 is arranged in the enclosure 1702. Thus, the power contact 1826 extends from the primary recess 1734a of the primary housing structure 1834 through the power recess 1934b into the enclosure 1702.

Similarly, the ground recess 1934c is L-shaped in cross-section, so as to receive therein and couple to the coupling portion 1828c of the ground contact 1828. The ground recess 1934c extends to the primary recess 1734a of the primary housing structure 1834, such that the contact portion 1828a of the ground contact 1828 is arranged therein. The ground recess 1934c also faces the interior of the enclosure 1702, such that the conductor portion 1828b (i.e., the conductor segments 1828b') of the ground contact 1828 is arranged in the enclosure 1702. Thus, the ground contact 1828 extends from the primary recess 1734a of the primary housing structure 1834 through the ground recess 1934c into the enclosure 1702.

The data recess 1934d is substantially circular in cross-section, so as to receive therein and couple to the data contact. The data recess 1934d is generally surrounded by the power recess 1934b and the ground recess 1934c. The data recess 1934d extends to the primary recess 1734a of the primary housing structure 1834, such that the contact portions of the data contact 1830 are arranged therein. The data recess 1934d also faces the interior of the enclosure 1702, such that the data contact 1830 extends into the enclosure 1702. Thus, data contact 1830 extends from the primary recess 1734a of the primary housing structure 1834 through the data recess 1934d into the enclosure 1702.

The external housing structure 1836 is configured to mechanically connect and seal the receptacle assembly 1720 to the enclosure 1702. The external housing structure 1836 is a generally annular structure or member. More particularly, the external housing structure 1836 is configured as a nut, which is threadably received by the primary housing structure 1834 (see threads in FIGS. 21A-21D). When tightened thereon, the external housing structure 1836 compresses the wall 1702a of the enclosure 1702 between the external housing structure 1836 and the shield plate 1824. Furthermore, the external housing structure 1836 may include or otherwise engage compressible seal members. For example, the external housing structure 1836 may compress in an axial direction a gasket 1840 (e.g., elastomeric O-ring) between a peripheral portion 1836a (e.g., configured as a radial flange) and a surface of the wall 1702a of the enclosure 1702. The gasket 1840 may be arranged in an axially facing groove of the peripheral portion 1836a, such that the peripheral portion 1836a may engage the wall 1702a and appropriately compress the gasket 1840 thereagainst. Another gasket 1842 may be arranged and compressed radially between the primary housing structure 1834 and the external housing structure 1836. The gasket 1840 and the gasket 1842, thereby, cooperatively, seal the receptacle assembly 1720 to the enclosure 1702. The external housing structure 1836 is, for example, an injection molded polymer component (e.g., polyamide). The external housing

structure **1836** may also be referred to as a nut or a housing coupling member or structure.

The internal housing structure **1838** is arranged within the enclosure **1702** and, for example, prevents contact between the conductor segments **1826b'**, the conductor segments **1828b'**, and the data contact **1830**, themselves, and prevents inadvertent electrical contact with other electrical components (e.g., of the circuit board). The internal housing structure may, as shown, include a first cover member **1838a** and a bottom cap **1838b**, each of which may be an injection molded polyamide component.

With further reference to FIGS. 19A-19F, an assembly sequence of the receptacle assembly **1720** is described. As shown in FIG. 19A, the primary housing structure **1834** is provided.

As shown in FIG. 19B, the power contact **1826** and the ground contact **1828** are inserted into the power recess **1934b** and the ground recess **1934c**, respectively. During insertion, the conductor segments **1826b'** of the power contact **1826** and the conductor segments **1828b'** of the ground contact **1828** remain straight (e.g., extending rearward parallel with an axis of the primary housing structure **1834**).

As shown in FIG. 19C, the conductor segments **1826b'** and the cylindrical portions **1826c'** of the power contact **1826** and the conductor segments **1828b'** and the cylindrical portions **1828c'** of the ground contact **1828** are inserted into the power apertures **1824a** and the ground apertures **1824b**, respectively, of the shield plate **1824**. The shield plate **1824** is also moved axially toward the primary housing structure **1834** and abuts a rear end thereof. It should be noted that the shield plate **1824** is larger (e.g., has a larger diameter) than the primary housing structure **1834**, such that edges of the shield plate **1824** extend radially outward past edges of the primary housing structure **1834** to abut forward against an internal surface of the wall **1702a** of the enclosure **1702** surrounding the aperture **1802b**.

As shown in FIG. 19D, the conductor segments **1826b'** of the power contact **1826** are then bent transverse to the axis of the primary housing structure **1834**. Threaded fasteners **1938** are threaded through screw apertures **1824d** of the shield plate **1824** and into threaded bores **1934e** of the primary housing structure **1834** to mechanically couple the shield plate **1824** to the primary housing structure **1834**.

As shown in FIG. 19E, the data contact **1830** is inserted through the data aperture **1824c**, such that the rearward portion **1830a'** of the data contact **1830** abuts the shield plate **1824**.

As shown in FIG. 19F, the conductor segments **1828b'** of the ground contact **1828** are bent transversely downward (e.g., to be parallel with and terminate at a common height with the conductor segments **1826b'** of the power contact **1826**). The internal housing structure **1838** is then connected to the primary housing structure **1834** with other threaded fasteners **1938** that extend through the screw apertures **1824d** of the shield plate **1824** and into threaded bores **1934e** of the primary housing structure **1834**. The primary housing structure **1834** may press the data contact **1830** axially against the shield plate **1824**.

With further references to FIGS. 21A-21D, the receptacle assembly **1720** is then connected to the enclosure **1702**. More particularly, the primary housing structure **1834** is inserted through the apertures **1802b** in the wall **1702a** of the enclosure **1702** until the shield plate **1824** engages the wall **1702a**. More particularly, a rearmost portion of the primary housing structure **1834** may remain in the aperture **1802b** of the enclosure **1702**, while the shield plate **1824** extends

radially outward thereof (as noted above) and is abutted axially against an interior surface of the wall **1702a**.

The external housing structure **1836** is then threaded to the primary housing structure **1834**. The external housing structure **1836** is further tightened, so as to press the shield plate **1824** against the wall **1702a** and to compress the gasket **1840** between the external housing structure **1836** and an external surface of the wall **1702a**. It should be noted that the shield plate **1824** may, rather than have a planar surface that engages the enclosure **1702**, include various protrusions, clips, or other features to ensure constant (e.g., regular or repeating) contact with the enclosure **1702** around the aperture **1802b**.

Referring to FIG. 20, the plug assembly **1750** generally includes an outer housing structure **2052**, an inner housing structure **2054**, a power contact **2056**, a ground contact **2058**, a data contact **2060**, and wire seal **2062**. Generally speaking, the power contact **2056** is configured to electrically connect a power wire **2056a**, and in particular a single conductor thereof, to the power contact **1826** of the receptacle assembly **1720** (e.g., forming a power pathway). The ground contact **2058** is configured to electrically connect a ground wire **2058a**, and in particular a single conductor thereof, to the ground contact **1828** of the receptacle assembly **1720** (e.g., forming another power or ground pathway). These single conductors may be stranded or solid, but are to be distinguished from separately insulated wires. The data contact **2060** is configured to electrically connect both a data shield and a data conductor of a data wire to the shield member **1830a** and the conductor **1830b** of the data contact **1830**. The outer housing structure **2052** and/or the inner housing structure **2054** are mechanically connected to the power contact **2056**, the ground contact **2058**, and the data contact **2060**. The outer housing structure **2052** is further configured to be inserted into and engage the receptacle assembly **1720** to retain the plug assembly **1750** therein and seal therewith. The wire seal **2062** is configured to prevent intrusion of contaminants into the plug assembly **1750** and to align the power contact **2056**, the ground contact **2058**, and the data contact **2060** within the outer housing structure **2052**.

The power contact **2056** is connected to a power wire **2056a**, particularly a single conductor thereof, to conduct electricity therebetween. The power contact **2056** is further configured to physically contact and, thereby, electrically couple to the contact portion **1826a** of the power contact **1826** in the receptacle assembly **1720**. The power contact **2056** includes multiple fingers **2056b** (e.g., power fingers) that extend generally in an axial direction from the power wire **2056a**. The fingers **2056b** are configured to engage the power contact **1826** of the receptacle assembly and flex (e.g., deflect) independent of each other. The fingers **2056b** form sprung and redundant mechanical engagement with the contact portion **1826a** of the power contact **1826** to ensure a robust electrical connection. In cross-section, in a proximal region of the power contact **2056**, the multiple fingers **2056b** cooperatively form a transverse arc that is complementary to the curvature of the power contact **1826** of the receptacle assembly **1720**. In an intermediate region of the power contact **2056**, the fingers **2056b** may additionally extend radially outward (e.g., flare or taper outward), so as to increase a radius of the transverse arc. In a distal region of the power contact **2056**, the fingers **2056b** may extend axially, such that the transverse arc has a larger radius than in the intermediate region. The fingers **2056b** are also configured to deflect independent of each other.

As a result of the complementary curvature (i.e., transverse arc), flared distal ends, and independent deflection, the fingers 2056b are configured to receive radially therein and physically contact the contact portion 1826a of the power contact 1826. The power contact 2056, thereby, electrically connects the power wire 2056a to the power contact 1826 of the receptacle assembly 1720.

The power contact may, for example, be made of a copper alloy formed, for example, in a stamping operation. The power contact 2056 is supported by the outer housing structure 2052 and/or the inner housing structure 2054, as will be discussed below, to ensure reliable connection to the power contact 1826 of the receptacle assembly 1720.

The ground contact 2058 is configured substantially similar to the power contact 2056. The ground contact 2058 is connected to a ground wire 2058a, particularly a single conductor thereof, and is configured to physically contact and, thereby, electrically couple to the contact portion 1828a of the ground contact 1828 in the receptacle assembly 1720. The ground contact 2058 includes multiple fingers 2058b (e.g., ground fingers) that extend generally in an axial direction from the ground wire 2058a. For further details of the ground contact, including the multiple fingers 2058b, refer to discussion of the power contact 2056 above.

As arranged in the plug assembly 1750, the power contact 2056 is arranged radially opposite the ground contact 2058. The power contact 2056 and the ground contact 2058, thereby, define a recess for receiving therein and contacting the power contact 1826 and the ground contact 1828 of the receptacle assembly 1720. In the distal and intermediate regions, the recess defined between the power contact 2056 and the ground contact 2058 may be generally cylindrical and/or frusto-conical to facilitate receipt of the power contact 1826 and the ground contact 1828 therein.

The data contact 2060 is connected to a data wire 2060a to conduct data signals therebetween and also connect shielding of the data wire 2060a to the shield 1824 and the enclosure 1702. The data wire 2060a includes a shield (not labeled) and a dielectric (not labeled) that surround a central conductor (not labeled). The data wire 2060a may, for example, form or be connected to the data conductor 561 and the shielding layer 563 of the cable 160. The data wire 2060a may, for example, be coax or similar. The data contact 2060 includes a shield contact portion 2060b and a data contact portion 2160c that are, respectively, electrically connected to the shield and the central conductor of the data wire 2060a. The data contact portion 2160c may be seen in FIGS. 21A-21D. The shield contact portion 2060b and the data contact portion 2160c are further configured to physically contact and, thereby, electrically couple to the shield member 1830a and the conductor 1830b of the data contact 1830 of the receptacle assembly 1720, which thereby form a data pathway for transferring data and a shield pathway (e.g., electrically connecting or grounding the shield of the data wire 2060a to the enclosure 1702). The shield contact portion 2060b is, for example, received by the shield member 1830a. The shield member 1830a is, thereby, electrically coupled to the shield plate 1824 and the enclosure 1702. The data contact portion 2160c may, for example, receive the conductor 1830b of the data contact 1830 of the receptacle assembly 1720 therein.

The inner housing structure 2054 is mechanically connected to the power contact 2056, the ground contact 2058, and the data contact 2060, so as to facilitate contact with the power contact 1826, the ground contact 1828, and the data contact 1830, respectively, of the receptacle assembly 1720 when inserted therein. The inner housing structure 2054 is a

generally annular member having a proximal portion 2054a and a distal portion 2054b. The proximal portion 2054a is generally configured to couple to and/or otherwise support the power contact 2056, the ground contact 2058, and the data contact 2060. The distal portion 2054b defines a recess 2054c in which the power contact 2056, the ground contact 2058, and the data contact 2060 are positioned, and in which the power contact 1826, the ground contact 1828, and the data contact 1830 of the receptacle assembly 1720 are received.

Furthermore, the power contact 2056, the ground contact 2058, and the data contact 2060 of the plug assembly 1750 may be cooperatively configured with the power contact 1826, the ground contact 1828, and the data contact 1830 of the receptacle assembly 1720 to facilitate electrical connections being performed in a particular order or sequence. For example, as the plug assembly 1750 is inserted into the receptacle assembly 1720, the ground contacts 2058, 1828 first connect with each other, then the power contacts 2056, 1826 connect with each other, then the data contacts 2060, 1830 connect with each other. This ordered sequence of connections may be to ensure proper power sequencing and/or to prevent effects of arcing and electrostatic discharge. Conversely, when the plug assembly 1750 is removed, the data contacts 2060, 1830 first disconnect from each other, then the power contacts 2056, 1826 disconnect from each other, then the ground contacts 2058, 1828 disconnect from each other. Such ordered or sequenced connections may be facilitated, for example, by the respective lengths of the contacts. Referring to the schematic detail view of FIG. 21E, for example, prior to connection (e.g., when the plug assembly 1750 is partially inserted into the receptacle assembly 1720), the ground contacts 2058, 1828 are in closer axial proximity to each other than are the power contacts 2056, 1826, and the power contacts 2056, 1826 are in closer axial proximity to each other than the data contacts 2060, 1830.

The proximal portion 2054a of the inner housing structure 2054 defines a bore through which the data wire 2060a and the data contact 2060 extend. The data contact 2060 is, further, supported by the proximal portion 2054a to be suspended in the distal portion 2054b for connection to the data contact 1830 of the receptacle assembly 1720.

The power wire 2056a and the ground wire 2058a extend parallel with the proximal portion 2054a and are positioned radially opposite each other. The power wire 2056a and the ground wire 2058a may, for example, form or be coupled to the conductors 568 of the cable 160. The power contact 2056 and the ground contact 2058 may each be connected and/or otherwise supported by the inner housing structure 2054. The distal portion 2054b additionally includes apertures 2054d in which the fingers 2056b of the power contact 2056 and the fingers 2058b of the ground contact 2058 are arranged to engage the power contact 1826 and the ground contact 1828 when received in the recess thereof.

The inner housing structure 2054 is, for example, an injection molded polymer (e.g., polyamide) member, but may be made according to other manufacturing processes and/or different suitable materials.

The outer housing structure 2052 is a generally tubular structure (e.g., annular). The outer housing structure 2052 surrounds and contains therein the inner housing structure 2054, as well as the power contact 2056, the ground contact 2058, and the data contact 2060. The outer housing structure 2052 is configured to be inserted into the primary recess 1734a and releasably connect and seal to the primary housing structure 1834 of the receptacle assembly 1720. For

example, the outer housing structure **2052** may include a sprung lever **2052a** that engages the locking feature **1834a** of the primary housing structure **1834** of the receptacle assembly **1720**. A gasket **2064** (e.g., a polymer O-ring) may also be arranged and compressed radially between the outer housing structure **2052** of the plug assembly **1750** and the primary housing structure **1834** to form the seal therebetween.

The outer housing structure **2052** is, for example, an injection molded polymer (e.g., polyamide) member, but may be made according to other manufacturing processes and/or different suitable materials.

The wire seal **2062** is configured to support the power wire **2056a**, the ground wire **2058a**, and the data wire **2060a** in a proximal end of the outer housing structure **2052**. The wire seal **2062** additionally forms a seal with the outer housing structure **2052** and/or the inner housing structure **2054**, as well as forms seals with the power wire **2056a**, the ground wire **2058a**, and the data wire **2060a** extending axially therethrough. The wire seal **2062** is, for example, an injection molded elastomeric component.

The plug assembly **1750** may additionally include a housing cover **2066**, which is received over the distal end of the outer housing structure **2052**. The housing cover **2066** is coupled to the outer housing structure **2052** (e.g., with snap-fit arrangement) to retain the wire seal **2062** therein.

The plug assembly **1750** may additionally include a terminal position assurance member **2168**, which is arranged radially between the inner housing structure **2054** and the outer housing structure **2052**. The terminal assurance member **2168** is a structure, which may function to align and/or support the power contact **2056** and the ground contact **2058** in proper positions in the plug assembly **1750**.

What is claimed is:

1. A connector system for transferring electricity and data signals, the connector system comprising:

a receptacle comprising a shield, a power contact, a ground contact, and a data contact, wherein the shield provides electromagnetic shielding and includes one or more power apertures through which the power contact extends, one or more ground apertures through which the ground contact extends, and a data aperture through which a shield member and a data conductor of the data contact extend; and

a plug comprising another power contact connected to a power wire conductor, another ground contact connected to a ground wire conductor, and another data contact, wherein the plug is selectively receivable by the receptacle to electrically connect the power wire conductor to the power contact of the receptacle, to electrically connect the ground wire conductor to the ground contact of the receptacle, and to electrically connect the data contact to the other data contact.

2. The connector system according to claim 1, wherein the shield is connectable to an enclosure containing one or more electrical components to which the electricity and the data signals are transferable.

3. The connector system according to claim 2, further comprising the enclosure.

4. The connector system according to claim 2, wherein a cable is connected to the plug and includes a data conductor and a shielding layer, and when the plug is received by the receptacle to electrically connect the data contact to the other data contact, the shielding layer is electrically connected to the shield member to form a shield pathway from the shielding layer to the enclosure.

5. The connector system according to claim 2, wherein when the plug is received by the receptacle, a seal is formed between the plug and the receptacle.

6. The connector system according to claim 5, wherein the plug includes a gasket that is compressed between the plug and the receptacle to form the seal, and the seal prevents water intrusion into the enclosure.

7. The connector system according to claim 1, wherein the power contact is positioned radially opposite the ground contact, and the data contact extends axially between the power contact and the ground contact.

8. The connector system according to claim 1, wherein the shield includes two or more of the power apertures and two or more of the ground apertures;

15 wherein the power contact includes two or more power conductor segments, one of the power conductor segments extending through each one of the power apertures; and

wherein the ground contact includes two or more ground conductor segments, one of the ground conductor segments extending through each one of the ground apertures.

9. The connector system according to claim 8, wherein the power contact includes a power contact portion that engages the other power contact of the plug, and the power conductor segments conduct electricity from the power contact portion through the shield, the power contact portion and the power conductor segments forming a singular conductive member; and

30 wherein the ground contact includes a ground contact portion that engages the other ground contact of the plug, and the ground conductor segments conduct electricity from the power contact portion through the shield, the ground contact portion and the ground conductor segments forming another singular conductive member.

10. The connector system according to claim 9, wherein the other power contact of the plug includes power fingers that engage the power contact portion of the receptacle and that flex independent of each other; and

40 wherein the other ground contact of the plug includes ground fingers that engage the ground contact portion of the receptacle and that flex independent of each other.

45 11. The connector system according to claim 8, wherein the power apertures are arranged in a first group, the ground apertures are arranged in a second group, and the data aperture is arranged between the first group and the second group.

50 12. The connector system according to claim 11, wherein the power conductor segments extend through the shield parallel with the ground conductor segments in an axial direction.

13. The connector system according to claim 1, wherein the shield is connectable to an enclosure containing one or more electrical components to which the electricity and the data signals are transferable;

60 wherein a cable is connected to the plug and includes a data conductor and a shielding layer, and when the plug is received by the receptacle, a shield pathway is formed from the shielding layer to the enclosure;

wherein when the plug is received by the receptacle, a seal is formed between the plug and the receptacle by a gasket that is compressed therebetween to prevent water intrusion into the enclosure;

65 wherein the shield includes two or more of the power apertures and two or more of the ground apertures, the

power contact includes two or more power conductor segments with one of the power conductor segments extending through each one of the power apertures, and the ground contact includes two or more ground conductor segments with one of the ground conductor segments extending through each one of the ground apertures;

wherein the power contact includes a power contact portion that engages the other power contact of the plug, and the power conductor segments conduct electricity from the power contact portion through the shield, and wherein the ground contact includes a ground contact portion that engages the other ground contact of the plug, and the ground conductor segments conduct electricity from the power contact portion through the shield; and

wherein the other power contact of the plug includes power fingers that engage the power contact portion of the receptacle and that flex independent of each other, and the other ground contact of the plug includes ground fingers that engage the ground contact portion of the receptacle and that flex independent of each other.

14. The connector system according to claim 1, wherein the shield is formed by an electromagnetic shield structure having a rear shield structure and a peripheral shield structure extending forward from the rear shield structure, and the one or more power apertures, the one or more ground apertures, and the data aperture extend through the rear shield structure.

15. The connector system according to claim 14, wherein the electromagnetic shield structure further includes a forward shield structure electrically connected to the peripheral shield structure substantially continuously therearound, such that the electromagnetic shield structure surrounds the power contact and the ground contact and receives the other power contact and the other ground contact of the plug therein.

16. The connector system according to claim 15, wherein the receptacle includes a body member contained within the electromagnetic shield structure, and the body member receives the plug to form a seal therewith.

17. A connector system for transferring electricity and data comprising:

a receptacle assembly including a housing, a shield plate, a power contact, a ground contact, and a data contact, wherein the shield plate provides electromagnetic shielding, is connected to the housing, and includes multiple power apertures through which the power contact extends, multiple ground apertures through which the ground contact extends, and a data aperture through which the data contact extends;

a plug assembly including another housing, another power contact, another ground contact, and another power contact in the other housing, the plug assembly being receivable by the receptacle assembly to form a seal therebetween and to electrically connect the other power contact to the power contact, the other ground contact to the ground contact, and the other data contact to the data contact;

wherein the receptacle assembly is configured to connect to an electromagnetic shield enclosure to form a seal therewith and to electrically connect the shield plate thereto.

18. The connector system according to claim 17, wherein the receptacle assembly is configured to couple to the electromagnetic shield enclosure by extending through an

enclosure aperture of the enclosure with the shield plate contacting the enclosure entirely around the enclosure aperture.

19. The connector system according to claim 18, wherein the seal is formed by compressing a seal member between the housing and the electromagnetic shield enclosure, the seal member being positioned radially outward of the enclosure aperture.

20. The connector system according to claim 17, wherein the power contact includes three power conductor segments and the shield plate includes three power apertures through which the power conductor segments extend, and the ground contact includes three ground conductor segments and the shield plate includes three ground apertures through which the ground conductor segments extend.

21. A connector system for providing power and data coupling, comprising:

a cable having a data conductor, a shielding layer, a first power conductor, and a second power conductor; a plug connector mechanically coupled to the cable and comprising a first data terminal electrically coupled to the data conductor, a first annular member electrically coupled to the shielding layer, a first power terminal electrically coupled to the first power conductor, a second power terminal electrically coupled to the second power conductor, and an outer annular member, wherein the first annular member is positioned radially between the first power terminal and the second power terminal, the first data terminal is positioned within the first annular member, and the outer annular member surrounds the first data terminal, the first annular member, the first power terminal, and the second power terminal; and

a base configured to receive the plug connector, the base comprising a shield structure providing electromagnetic shielding and defining a cavity in which are positioned a second data terminal, a second annular member, a third power terminal, and a fourth power terminal, which are configured to electrically couple to the first data terminal, the first annular member, the first power terminal, and the second power terminal of the plug connector, respectively;

wherein the base further comprises a body in the cavity of the shield structure, and the body defines a recess for receiving the plug connector to seal therewith and in which are positioned the second data terminal, the second annular member, the third power terminal, and the fourth power terminal, the recess receiving and having a larger diameter than the outer annular member of the plug connector.

22. The connector system according to claim 21, wherein the base includes a front plate electrically coupled to a forward edge of the shield structure and extending laterally outward therefrom.

23. The connector system according to claim 22, wherein the shield structure is recessed into and electrically connected to an enclosure.

24. The connector system according to claim 8, wherein the power contact includes overmolded portions that surround the power conductor segments to prevent conductive contact with the shield, and ground contact includes other overmolded portions that surround the ground conductor segments to prevent conductive contact with the shield.

25. The connector system according to claim 10, wherein the power contact portion and the ground contact portion are positioned radially opposite each other and each form a portion of a cylindrical surface.

26. The connector system according to claim 20, wherein the power contact includes a power contact portion formed as a singular conductive member with the three power conductor segments, and the ground contact includes a ground contact portion formed as another singular conductive member with the three ground conductor segments. 5

27. The connector system according to claim 23, wherein the front plate is sealed with the body.
